UNITED STATES PATENT OFFICE.

THOMAS W. MORGAN, OF OAKLAND, CALIFORNIA.

VENTILATING MAN-HOLES FOR SEWERS.

SPECIFICATION forming part of Letters Patent No. 388,993, dated September 4, 1888.

Application filed June 2, 1888. Serial No. 275,857. (No model.)

To all whom it may concern:

Be it known that I, THOMAS W. MORGAN, of Oakland, Alameda county, State of California, have invented an Improvement in Ventilating Man-Holes for Sewers; and I hereby declare the following to be a full, clear, and exact description of the same.

My invention relates to a means for ventilating the man-holes of sewers; and it consists of a supplemental flue or chimney built in the wall of the vertical man-hole and connected therewith at or near the bottom of the flue, and an opening through the side of the man-hole curve or cover communicating with the upper part of the flue, together with a lip upon the inside of the curb or cover below this opening, and a pan or cover resting upon the lip and closing the main opening and causing the current of air from the sewer to go through the flue; also a pan to catch all dirt, sticks, &c., which may fall through the openings in the top cover.

Referring to the accompanying drawings for a more complete explanation of my invention, Figure 1 is a vertical section of the man-hole curb and supplemental chimney, taken through A B of Fig. 3. Fig. 2 is a vertical section taken through C D of Fig. 3. Fig. 3 is a horizontal section taken through E F of Fig. 1. Fig. 4 is the top view of the curb and extension-cover of the supplemental chimney.

A is a vertical chimney or man-hole extending from the street-surface down to the sewer B, which passes beneath and in communication with its lower end. The upper part of the man-hole is finished off by a circular iron curb, C, having a perforated cover, D, which lies flush with the street-surface.

In my invention I have built a supplemental vertical flue or chimney, E, at one side of and parallel with the man-hole. The lower end of this flue connects with the man-hole at some convenient or desirable point between the top and bottom, and the opening is covered by a lattice or grating, F, as shown in Fig. 2. The cover D for the man-hole has an extension, D', at one side, which forms a cover for the supplemental flue, and a hole or opening, G, is made in the side of the cylindrical curb or cover, which communicates with the upper end of the supplemental flue.

Around the lower inner edge of the main

cylindrical curb is formed a projecting lip, H, upon which the edges of the metal pan or cover I rest. This pan has an eyebolt or handle, K, by which it may be lifted out when the perforated cover is removed from the curb, and when it is in place it serves to prevent sticks and dirt from falling down into the man-hole and clogging the sewer.

The supplemental flue or passage may be filled with charcoal or other disinfectant substances, and the gases arising from the sewer passing up the man-hole will enter this flue through the lattice or grating, and thus rising to the top will again return into the curb above the pan I, through the opening G, and from thence will escape into the open air.

By this construction I provide a free escape for the gases arising from the sewer, and, if desired, a means for purifying them before their escape, while by means of the cover within the curb I prevent everything falling in, to form an obstruction in the man-hole or sewer.

Having thus described my invention, what I claim as new, and desire to secure by Letters Patent, is—

1. The vertical man-hole having the supplemental flue formed parallel therewith, and the curb C, having the opening G, said supplemental flue having its lower end leading into the man-hole and its upper end in communication with a close pan or cover at the bottom of the curb below the opening G, substantially as herein described.

2. The vertical man-hole, a supplemental flue built in the side wall thereof, and the curb C, said supplemental flue connecting with the man-hole at its lower end and with the space in the cylindrical curb at the upper end and being filled with charcoal or other disinfectant, in combination with the close pan or cap fitting upon the ledge or lip around the bottom of the curb, the perforated cover fitted to the curb, and the extension at the side of the curb with its supplemental cover, substantially as herein described.

In witness whereof I have hereunto set my hand.

THOMAS W. MORGAN.
